FIG. 1.

FIG. 2.

INVENTOR

Cornelius D. Ehret

UNITED STATES PATENT OFFICE.

CORNELIUS D. EHRET, OF PHILADELPHIA, PENNSYLVANIA.

METHOD OF AND APPARATUS FOR PRODUCING X-RAYS.

1,337,349.

Specification of Letters Patent. Patented Apr. 20, 1920.

Application filed November 13, 1918. Serial No. 262,277.

To all whom it may concern:

Be it known that I, CORNELIUS D. EHRET, a citizen of the United States, residing in the city and county of Philadelphia, State 5 of Pennsylvania, have invented a new and useful Method of and Apparatus for Producing X-Rays, of which the following is a specification.

My invention resides in an X-ray tube 10 comprising an anti-cathode or target spaced *in vacuo* from a cathode which reemits electrons or emits secondary electrons as a result of bombardment by primary electrons emitted by a body which does not directly 15 operate with the target or anti-cathode and which may be disposed outside of the chamber containing the target, as in an evacuated tube or bulb attached to the principal bulb.

My invention resides also in the method 20 of producing X-rays hereinafter described.

For an illustration of some of the various forms my invention may take, reference is to be had to the accompanying drawing, in which:

Figure 1 is a side elevation, partly in section, of an X-ray tube embodying my invention.

Fig. 2 is a side elevation, partly in section, of another form my invention may take.

Referring to Fig. 1, T is an X-ray tube 30 of glass or other suitable material having therein the anti-cathode or target A whose face as usual is of tungsten or other suitable refractory material. Spaced from the 35 target A is the cathode C, of platinum or other suitable material, of any suitable form, here shown of usual cup form, sealed around its edge or periphery to the inner end of the hollow glass stem S attached to the main 40 tube or bulb T and completely closed or sealed to form a chamber D separate from the main bulb T. Cathode C seals the two chambers from each other and forms a wall common to them.

The chamber D is highly exhausted, and 45 preferably to such degree that substantially pure electron discharge takes place therein, though the presence of gas or ionizable material is also within my invention. The 50 primary electron emitting body F is, in the example illustrated, a tungsten or other suitable filament brought to suitably high temperature or incandescence by current from the source b and adjusted as to 55 strength by the variable resistance r.

From cathode C there extends to the ex-

terior a conductor, as c, which, as illustrated, may be sealed or inclosed within a wall of stem S.

In the main bulb T is a vacuum suitable 60 for production of X-rays. It may be so high as to permit passage of current only by substantially pure electron discharge; or it may be of lesser degree as provided by presence of gas or ionizable material, and in 65 such case the degree of vacuum may be varied or controlled by any suitable type of vacuum regulators known in the art. And upon the side of cathode C facing target A may be a coating of suitable oxid or oxid 70 mixture, as of barium, calcium, strontium or other suitable material.

The vacua in chambers D and T may be 75 of equal or unequal degrees and of similar or dissimilar kinds above referred to.

The source of current B, of any suitable character and of suitable voltage, has its one terminal connected by conductor c to cathode C and its other terminal to the electron emitting body F. When body F is 80 negative with respect to cathode C the electrons emitted by body F strike at high velocity on the side of cathode C facing body F; as a result cathode C reemits electrons or 85 emits secondary electrons in far greater quantity than emitted by body F. The source of current B¹, of any suitable character and of suitable voltage, as from 30,000 to 150,000 or more volts, depending on character of results required and the degree and 90 character of vacuum in tube T, is connected to cathode C and to anti-cathode A. When the anti-cathode is positive with respect to cathode C, the greater quantity of electrons emitted by cathode C strike target A at 95 extremely high velocity and produce X-rays of great intensity or quantity.

When the vacuum in chamber D is so high that substantially pure electron discharge occurs therein, filament F will have 100 a long life because not bombarded by positive ions, while at the same time in the main bulb gas or ionizable material may be employed at lesser degree of vacuum than in chamber D.

In Fig. 2, the primary electron emitting body F is disposed in the bulb or tube T in which the vacuum may be of any of the degrees or characters referred to in connection with Fig. 1. It is again shown as a 110 filament whose temperature is controlled by variable resistance r. It is housed within

the shield E, of glass or other suitable material, intervening between body F and anode A and open at its end toward cathode C. Here again cathode C is bombarded by electrons from body F and reemits electrons in larger quantity which strike target A at extremely high velocity and produce X-rays.

What I claim is:

1. The method of producing X-rays, which consists in exciting a body to emit primary electrons, bombarding a cathode by said primary electrons to cause reemission of secondary electrons, and bombarding an anti-cathode to produce X-rays by secondary electrons reemitted by said cathode to the exclusion of bombardment by said primary electrons.

2. The method of producing X-rays, which consists in bombarding through a vacuum a cathode by electrons to cause reemission from said cathode into another vacuum, and bombarding an anti-cathode by electrons reemitted by said cathode to produce X-rays.

3. Apparatus for producing X-rays comprising a source of electrons, a cathode, means producing a difference of potential between said source and said cathode whereby said cathode is bombarded by electrons from said source and caused to reemit electrons, an anti-cathode disposed in a vacuum with said cathode and subjected to bombardment only by electrons reemitted from said cathode, and means producing a difference of potential between said anti-cathode and said cathode for effecting said second named bombardment.

4. An X-ray tube comprising an evacuated vessel, an imperforate cathode and an anti-cathode therein, a heated cathode discharge between which and said anti-cathode is prevented by said cathode, and means for maintaining said cathode at a potential higher than said heated cathode and lower than said anti-cathode, whereby said cathode is bombarded by emissions from said heated cathode and said anti-cathode is bombarded by reemissions from said cathode.

5. An X-ray tube comprising evacuated chambers, a cathode forming a sealing wall common to said chambers, a body in one of said chambers emitting electrons bombarding said cathode, and an anti-cathode in an-

other of said chambers bombarded by electrons reemitted by said cathode.

6. An X-ray tube comprising a main evacuated bulb, an anti-cathode therein, an evacuated stem on said bulb, a cathode forming a sealing wall between said main bulb and said stem, and a body in said stem emitting electrons bombarding said cathode.

7. An X-ray tube comprising a bulb, a cathode and an anti-cathode therein, a separate chamber evacuated to a degree suitable for substantially pure electron discharge, and a body in said chamber emitting electrons bombarding said cathode, said bulb evacuated to lesser degree than said chamber and containing ionizable material, said cathode forming a wall common to said chamber and said bulb.

8. An X-ray tube comprising an evacuated chamber, an anti-cathode therein, a co-operating cathode forming a sealing wall of said chamber, and means external to said chamber for causing said cathode to emit electrons into said chamber.

9. An X-ray tube comprising an evacuated chamber, a cathode, a co-operating anti-cathode in said chamber, an electron-emitting body for exciting said cathode by bombardment to cause reemission of electrons, and means limiting the bombardment of said anti-cathode to electrons reemitted by said cathode.

10. An X-ray tube comprising an evacuated chamber, a cathode, a co-operating anti-cathode in said chamber, a stem on said chamber, a body in said stem emitting electrons bombarding said cathode to cause reemission of electrons, and structure relating said cathode with respect to said body and said anti-cathode to prevent direct emission from said body to said anti-cathode.

11. An X-ray tube comprising an evacuated chamber, an anti-cathode therein, a cathode having an electron-emitting face within said chamber, and electron-emitting means within a space completely isolated from said chamber for bombarding said cathode to cause reemission from its said emitting face to said anti-cathode.

In testimony whereof I have hereunto affixed my signature this 12th day of November, 1918.

CORNELIUS D. EHRET.
